HOUSING FOR COMMUNICATION LISTENING STATION OR THE LIKE

Donald L. Kliewer, Minneapolis, Minn., assignor to The
Telex Corporation, Tulsa, Okla.

Filed Aug. 29, 1969, Ser. No. 18,914

Term of patent 14 years

Int. Cl. D13—03

U.S. Cl. D26—13

FIG. 1 is a perspective view of a housing for communication listening station or the like illustrating my invention;

FIG. 2 is a top plan view of the design shown in FIG. 1 of the drawings;

FIG. 3 is an end elevational view looking toward FIG. 1 of the drawings;

FIG. 4 is a side elevational view looking toward FIG. 1 of the drawings; and

FIG. 5 is a bottom plan view of the design shown in FIG. 1 of the drawings.

I claim:

The ornamental design for a housing for communication listening station or the like, as shown.
